UNITED STATES PATENT OFFICE.

WILLIAM THOMAS BUCKINGHAM ROBERTS, OF LEICESTER, ENGLAND, ASSIGNOR TO
UNITED SHOE MACHINERY CORPORATION, OF PATERSON, NEW JERSEY, A COR-
PORATION OF NEW JERSEY.

SKIVING MACHINE.

Application filed May 22, 1923, Serial No. 640,734, and in Great Britain June 2, 1922.

This invention relates to skiving machines and is herein illustrated as embodied in a machine for skiving the ends of strips of leather which are to be fastened together 5 with the skived ends overlapping to form a length of belting in the manufacture of belts.

The scarfs at the ends of these strips of material are of varying widths which sometimes reach a maximum of eight inches or more. It is essential that these scarfs be accurately cut since, when the two scarfed ends are overlapped and fastened together so as to join two strips, the thickness of the 15 joint should be uniform with the thickness of the solid portions of the strips, and there should be no ragged edges on the surface at the joint.

According to one feature of the invention 20 novel and improved means are provided for presenting to the skiving cutter the ends of the strips of material which are to be skived. The illustrative machine comprises a pair of feed rolls open at one end to provide space 25 for the passage of the body of the strip while the end thereof is being skived. A knife extends obliquely across the gap between the rolls and is mounted for angular movement about an axis located at that end of the rolls which is remote from the open 30 end. In front of the rolls is a table or support for the end portion of the strip and a gage for the extreme end edge of the strip, means being provided for pushing sidewise to the rolls the end portion of the strip thus supported and guided. With this construction an extremely accurate scarf may be produced.

This and other features of the invention, 40 including certain details of construction and combinations of parts, will be described as embodied in an illustrative machine and pointed out in the appended claims.

Referring now to the accompanying drawings:—

Figure 1 is a front elevation, partly broken away, of a machine in which the present invention is embodied.

Fig. 2 is a plan view of the machine partly broken away.

Fig. 3 is a side elevation of the machine.

Fig. 4 is a part sectional elevation on the line 4—4 of Fig. 3.

Fig. 5 is a part sectional elevation on the line 5—5 of Fig. 4. 55

Fig. 6 is a sectional detail of knife-carrying mechanism of the machine.

Fig. 7 shows, to an enlarged scale, a section of a comparatively soft piece of material being operated upon. 60

Fig. 8 is an end view of the mechanism shown in Fig. 7.

Fig. 9 illustrates diagrammatically the operation of certain parts of the machine upon a comparatively hard piece of material; and 65

Fig. 10 shows sections of a piece of material after it has been operated upon in the machine.

The main frame 1 of the machine has 70 bolted to it a horizontal table 2 along which the material to be scarfed or skived is fed, by the operator, to the feeding rolls. To enable the operator to feed the material squarely to the rolls and to force its leading 75 edge between them a plate 3 is slidingly mounted in a dove-tailed guideway formed in the table 2. The material may be the end of a wide piece of belting the bulk of which is rolled in a coil which is moved along its axis as its end on the table is moved laterally on to the knife. The plate 3 has at about the middle of it a hand-piece 4 by which the operator may slide the plate towards or from the rolls and a depending 80 stop 5 which, when the plate 3 is moved towards the rolls, engages the rear end of a second groove in the table to limit the movement of the plate 3 towards the rolls. The plate at its rear end has fixed on it a transverse bar 6 having fixed on it two leaf springs 7 which project beyond the rear edge of the bar and beneath which the front edge of the material is placed with its edge 85 against the bar. The end of the material is placed against a vertical guide face, on an upper roll-carrying frame 9, to be herein-after described, which face forms a guide for the end of the material.

The lower roll 10 (Fig. 4) has a smooth 100 surface and is keyed to a horizontal shaft 11, extending from left to right of the ma-

chine, rotatably mounted in bearings formed on a member 12 fixed in the main frame. The upper edge of the lower roll 10 is slightly above the upper surface of the table 5 2 and its inner or right-hand end bears against the guide face 8 on the upper-roll-carrying frame 9 which face extends well rearward into the plane of the roll axis and has let into it a hardened plate 116 (Fig. 5) 10 fixed by screws 117 to the frame 9 so as to guide the edge of the material as close up to the knife as possible. The end of the roll at this end is slightly enlarged in diameter (about $\frac{1}{16}$ "') as shown at 13 (Fig. 7) 15 and is curved or flared from the smaller to the larger diameter for a purpose to be hereinafter described.

The upper roll 14 is knurled and is formed as a sleeve fixed by a pin 15 (Fig. 4) to an 20 enlarged portion 16 of a shaft 17. The roll 14 extends into a bearing in the upper-roll-carrying frame 9 which frame is pivoted on a shaft 18 (Fig. 3) fixed in the frame 1. The shaft 17 (Fig. 4) at its right-hand end 25 enters a bore in a sleeve 19 rotatably mounted in a bush 20 fixed in the upper-roll-carrying frame 9. The shaft 17 can slide axially in the sleeve 19 and is keyed to it to rotate therewith. To adjust the upper 30 roll 14 axially the left-hand end of the shaft 17 is reduced at 21 and has a bearing in a sleeve 22 fixed in a depending portion of a slide 23 mounted in a guideway formed in the upper-roll-carrying frame 9 above and 35 parallel to the upper roll 14. The shaft 17 is held against endwise movement relatively to the slide by a washer 24 and nut 25 on the end of the reduced portion 21 of the shaft 17 (at one end of the sleeve 22) and 40 by the shoulder formed on the shaft 17 by the reduced portion 21 (at the other end of the sleeve). The slide 23 has fixed in it a handle 26 by which the slide 23 and roll 14 may be moved endwise and carries a plunger 45 arranged to enter one of a series of holes 45 28 formed in the upper-roll-carrying frame. The plunger 27 may be raised by a hand lever 29, pivoted on the handle 26, against the action of a spring 30. The holes 28 are 50 half an inch apart and are so arranged that a scarf from three and a half to eight and a half inches varying by half an inch may be cut, the width of scarf varying by the distance the upper roll 14 projects beyond 55 the guide face 8 on the upper-roll-carrying frame 9. The upper-roll-carrying frame 9 has a forwardly projecting arm 31 (Fig. 3) between the lower side of which and the main frame is confined a compression spring 32 which yields when the material enters 60 between the rolls. Movement of the upper roll 14 towards the lower roll under the influence of the compression spring 32, when there is no material between the rolls, is 65 limited by a hand wheel 33 screwed on to

the upper end of a rod 34 which passes through the compression spring 32 and through the arm 31 of the upper roll frame 9 and is fixed in the main frame 1. By adjusting the hand wheel 33 the space between the rolls may be varied to suit the thickness of the material. The tension of the spring 32 may be adjusted by means of a hand-wheel 35 threaded on the lower end 70 of the rod 34 on which hand-wheel the lower 75 end of the spring 32 rests.

Between the inside face of the depending bearing on the slide 23 and the end face of the upper roll 14 is an adjustable plate 36 (Figs. 4 and 8). The plate 36 projects from a block 37 vertically adjustable over a face 38 (Fig. 3) on the rear of the slide 23 by a vertical screw 39 threaded into the block and prevented from endwise movement by a lug 40 on the slide 23 which is engaged on one side by the head 41 of the screw and on the other side by a collar 42 on the screw. The block is guided over the face on the slide by a screw 43 passing through a vertical slot 44 (Fig. 7) in the block, into a threaded hole in the slide. The head 41 of the adjusting screw 39 has formed on it notches which are engaged by a spring plunger 45 carried in the slide 23 to prevent accidental rotation of the screw and to indicate the amount the block is adjusted when the screw is rotated. The plate 36 has fixed in it a hardened block 46 (Figs. 7, 8 and 9) which is set, by means of the screw 39, a little below the lower surface of the upper roll 14 so as to compress a portion of the material between the block and the lower roll, which lower roll, when cutting a scarf of the greatest width which the machine is 95 designed to cut, projects about one-half inch 100 beyond the outer or left hand end of the upper roll. The amount the lower roll projects beyond the upper roll increases as the upper roll is adjusted axially to cut a scarf 105 of less width.

The lower roll is actually formed in two parts, the part 10 on which is formed the flared end 13 being fixed to the shaft 11 by a key 47 (Fig. 7) while a part 48 of the roll is removable and is connected to the 115 part 10, so as to rotate therewith, by a pin 49.

When operating upon comparatively soft material the block 46 will readily compress, for a purpose hereinafter described, a portion of the material between itself and the part 48 of the lower roll, but if the material is comparatively hard it will not be compressed so readily; and to assist in the distortion of the work the part 48 of the lower 120 roll may be beveled as at 50 (see Fig. 9). The highest part of the beveled portion where it merges into the parallel portion of the part 48 is, in such a case, arranged to come in line with the inner face of the block 125 130

46, and in order that this alinement may be obtained, when the slide 23 is adjusted for the cutting of a different width of scarf, the part 48 is made detachable so that a similar 5 part having its beveled portion positioned differently, axially of the part, to suit the desired width of scarf may be substituted. For this purpose the end bearing 51 (Fig. 4) of the shaft 11 is detachably fixed by a 10 bolt 52 (Fig. 3) and hand-nut 53 to the member 12. By beveling the part 48 and positioning the high part of the bevel in relation to the block 46 as described only a very small portion of the material has to 15 be distorted, the material outside the rolls being bent bodily down as shown in Fig. 9. The edge of the compressed or bent portion (as the case may be) defines the edge of the scarf where the knife edge 54^a (see 20 Fig. 7, 8 and 9) extends out of the material; and, when the material passes from between the rolls, the compressed or bent portion expands or springs back with the result that a sharply defined concavely curved shoulder 25 or depression A (Fig. 10) is formed at the inner edge of the scarf. In a similar manner the flared end 13 of the lower roll produces a convex opposite end B (Fig. 10) to the scarf so that when two skived belt ends 30 come to be cemented together they will mate properly with the convex outer margin of the scarf on the one piece seated snugly in the concave inner margin of the scarf on the other piece.

35 The knife 54 has formed along each side a V groove, the groove on one side (the right-hand side as viewed in Fig. 1) being held against a V face 55 formed in a member 56 by a clamp 57 and screw 58. The cutting edge 54^a of the knife is positioned 40 in the member 56 by a plate 59 fixed on the member 56; and thrust on the knife due to the cutting of the scarf is resisted by an adjustable screw 60 threaded through a lug 45 61 on the member 56 and bearing against a block 62 resting on the knife and having a lip 63 (Fig. 3) engaging the back of the knife.

The member 56 is slidingly and rotatably 50 mounted on a rod 64 (Figs. 2 and 6) which is fixed by screws 65 to an arcuate slide 66 rotatably mounted in a bracket 67 fixed by a bolt 68 (Fig. 3) to the main frame 1. The bracket 67 has formed on it a tongue 69 55 which fits in a groove 70 in the frame. The axis of the arcuate slide 66 is in alinement laterally of the machine, with the face 8 and flared end of the lower roll 10 and heightwise of the machine, with the upper 60 edge of the flared end of the lower roll 10. The arcuate slide 66 is prevented from end- 65 wise movement in the bracket 67 by a block 71 (Fig. 5) positioned in a slot in the arcuate slide, fixed by a screw 72 to the bracket 67. A cap 73 extending from a

bracket 74 fixed by screws 75 to the bracket 67 holds the arcuate slide 66 on its seating in the bracket 67. The screw 72 clamps the cap 73, block 71 and bracket 67 together, the block being slightly thicker than the 70 slide 66 so as to allow movement of the slide. By removing the bolt 68 the bracket 67 and knife-carrying parts may be removed bodily from the machine for the removal or replacing of the knife. The rod 64 is supported at its left-hand end during the cutting by a face 100 (Fig. 2) formed on the bracket 74, which is engaged by a roll 101 on the rod.

A spring 76 tends to swing the slide 66 80 and knife in a clockwise direction (see Fig. 6) about the axis of the slide. The spring 76 is connected at one end to a bent rod 77 fixed in a lug 78 projecting from the bracket 67 and at the other end to a hook fixed in 85 a block 79 slidingly mounted in a bore in the rod 64. A screw 80 having fixed to it a hand-wheel 81 is threaded through the block 79 and is prevented from endwise movement in the shaft 64 so that when the screw is rotated the block 79 is moved axially of the 90 shaft to vary the tension of the spring 76.

The right-hand end (Fig. 7) of the cutting edge of the knife is supported on the narrow upper face of a slide 82 adjustable 95 vertically to vary the position of the knife edge at the point supported by the slide in relation to the upper edge of the bottom roll and thus to vary the thickness of the skived 100 edge of the material. The slide 82 (Figs. 3, 5 and 7) is guided in a bracket 83 fixed to the frame 1 and is adjusted by means of an eccentric portion of a shaft 84 which eccentric portion enters a slot in the slide. The shaft is rotatably mounted in the 105 bracket 83 and is adjusted by a hand-wheel 85 fixed on its end, there being a pointer 86 fixed on the shaft and index marks 87 on a segmental face on the bracket 83. Holes 88 are provided in the bracket into which 110 pins may be inserted, so that the shaft may be readily adjusted between two predetermined positions if desired. A plate 89 is fixed on the bracket 83 to guide downwardly 115 out of the machine the skived material.

The spring 76 holds the lower surface of the knife near its edge against the slide 82 and holds the upper surface of the knife at its left-hand end, near its edge, against a face on the under surface of the block 120 46 (but a little higher than the portion of the block which bears on the work) so that the active portion of the knife edge 54^a occupies a diagonal position from the lower left-hand edge of the top roll to the upper 125 right-hand edge of the lower roll, as shown in Fig. 7, and when the upper roll is adjusted axially for a different width of scarf, or when the upper roll is raised by the entrance of the work between the rolls, the 130

angle of the knife edge will vary accordingly. The width of the knife edge which is active will also vary when scarfs of different widths are being cut, and the scarf will always terminate at the outer edge of the upper roll. When it is desired to remove the bracket 67 and knife from the machine the pressure of the knife against the block 46 should be relieved to prevent damage to the knife or to the operator by the sudden swinging of the knife about the axis of the slide 66 under the influence of the spring 76; and, for this purpose, a hand-lever 189 (Fig. 6) is pivoted at 90 to the bracket 67. The hand-lever carries a roll 91 which, when the hand lever is swung into the position shown in Fig. 6, bears against the underside of the rod 64 which is thus prevented from swinging movement under the action of the spring 76. To ensure that the lever 189 shall have been moved into this position before the bracket 67 can be removed, the lever has formed on it a segment 92 which, when the bracket is fixed in the machine and the lever is moved to allow the spring 76 to swing the knife into engagement with the block 46, enters a slot in a lug 93 on the frame 1. The segment is so formed that it is not removable from the slot in the lug until the pressure of the knife on the block 46 has been relieved. The hand-lever 189 is held in this position against a stop face on the bracket 67 by the tension of the spring 76 acting on the roll 91 through the rod 64, the roll having moved just over the dead center. When the bracket is replaced the engagement of the segment and slot correctly positions the bracket in the machine.

When the upper roll 14 is adjusted axially by means of the slide 23 to vary the width of the scarf, the knife is simultaneously and correspondingly adjusted. For this purpose the member 56 (Fig. 2) is provided with a seating and cap for one end of a ball-ended link 94 the other end of which is seated in one end of an arm 95 the other end of which is mounted on a reduced portion 96 of the shaft 17. The reduced portion 96 is free to rotate in the arm, and the arm is confined axially of the shaft between the shoulder formed by the reduced portion 96 and a washer 97 fixed on the end of the shaft by a screw 98 so that the arm 95 moves with the shaft when it is moved axially and through the ball-ended link 94 causes the knife-carrying member 56 to slide axially on the rod 64. The arm 95 is prevented from swinging about the reduced portion 96 by a guide rod (not shown) fixed in the frame 1 and passing through the arm 95. When adjusting the top roll and knife it is advisable to relieve the pressure of the knife on the block 46 by means of the hand-lever 189 and to allow the knife to take up

its diagonal position only after the knife has been adjusted. By adjusting the knife with the upper roll, as described, the left-hand end of the knife is never exposed substantially beyond the block 46 as would be the case when cutting narrow scarfs; if the knife did not thus move with the roll, and injury to the operator by an exposed knife is in this way prevented. The knife at its right-hand end beyond the slide 82 is received in an opening 99 (Fig. 5) in the upper-roll-carrying frame 9. To prevent the operator's fingers from being drawn between the upper and lower rolls a telescopic guard comprising two bars 114, 115 fixed respectively to the face 8 of the member 9 and to the bearing for the reduced end 21 of the shaft 17 is provided.

Fixed or formed on the sleeve 19 is a pinion 102 which meshes with a pinion 103 rotatably mounted on a stud 104 fixed in the frame. The pinion 103 meshes with a pinion 105 rotatably mounted on a stud 106 fixed in the frame 1 and meshing with this latter pinion is a pinion 107 keyed to the lower roll shaft 11. The arrangement of these pinions (see Fig. 3) is such that as the upper and lower rolls are separated by the insertion of the material between them there is no disengagement of the teeth of any of the pinions.

Fixed on the sleeve 19 is a worm-wheel 108 which is driven by a worm 109 fixed on a shaft 110 rotatably mounted in bearings formed on a guard (a portion of which is shown at 111, Fig. 1) which encloses the pinions, worm-wheel and worm. The shaft 110 carries fast and loose pulleys 112, 113 by which the machine is driven.

In the operation of the machine, the end portion of a strip of sheet material such as belting is placed upon the support 2 with its end in contact with the guide 8. The pusher 6 is then manipulated to present the end portion of the strip sidewise to the rolls 10, 14. The left-hand end of the rolls, as viewed in Figs. 1 and 7, is open so that a free and unobstructed space is provided for the passage of the body of the strip while the end portion is being skived, the knife edge 54° being inclined downwardly across the gap between the rolls from the outer lowermost portion of that roll which is farthest from the plane of the support (the upper roll) to the inner uppermost portion of the other roll. As the skiving takes place the strip is bent along the lines in which the knife emerges from the surface, the member 46 and the flared inner end of the lower roll producing these bends, with the result that the scarf takes the form shown in Fig. 10.

Although the invention has been set forth as embodied in a particular machine, it should be understood that the invention is

not limited in the scope of its application to the particular machine which has been shown and described.

Having thus described my invention, 5 what I claim as new and desire to secure by Letters Patent of the United States is:—

1. A machine for skiving the end of a strip of sheet material having, in combination, a support for the end of the strip, a 10 pair of feed rolls one of which is farther than the other from the support, there being a free and unobstructed space at the outer ends of the rolls to permit passage of the body of the strip while the end thereof 15 is being skived, a knife, the effective portion of which extends substantially from the outermost strip-engaging point on that roll which is farther from the support to the innermost strip-engaging point on the other 20 roll, a guide adapted to engage the end of the strip, and means located near the guide for engaging the rear edge of the strip at a locality opposite that portion of the forward edge thereof which is to be presented 25 to the knife and pushing the end portion of the strip toward the knife.

2. A machine for skiving the end of a strip of sheet material having, in combination, a support for the end of the strip, a 30 pair of superposed feed rolls capable of relative movement of separation and approach, there being a free and unobstructed space at the outer ends of the rolls to permit passage of the body of the strip past 35 the rolls while the end of the strip is being skived, a knife the effective portion of the edge of which extends substantially from the outer lowermost portion of the upper roll to the inner uppermost portion of the 40 lower roll, a guide for the end of the strip arranged substantially perpendicular to the axes of the rolls and having its face substantially in line with the inner end of the lower roll, and a bar extending crosswise 45 of the support and mounted to slide lengthwise thereof for engaging the rear edge of the strip at a locality adjacent to the end of the strip whereby the end portion of the strip may be moved toward the knife and 50 held in parallel relation to the edge of the knife.

3. A machine for skiving the end portion of a strip of sheet material having, in combination, a support for the end of the strip, a pair of separable feed rolls open at 55 one end to permit passage of the body of the strip while the end thereof is being skived, a knife extending obliquely across the gap between the rolls from a point at 60 the outer end of one roll spaced a given distance from the plane of the support to a point on the other roll spaced a less distance from the support, means for varying the inclination of the knife in accordance 65 with the distance apart of the feed rolls, a

guide for the end of the strip, a push-bar extending crosswise of the support and mounted to slide lengthwise thereof, and a yielding member carried by the bar and adapted to press upon the upper face of 70 the end portion of the strip.

4. A machine for skiving the end portion of a strip of sheet material having, in combination, a pair of feed rolls, a knife having its edge extending obliquely across the gap 75 between the rolls, there being at one end of the rolls a free and unobstructed space for the passage of the body portion of the material, means whereby on roll may be adjusted in the direction of extent of its axis, 80 and a pusher adapted to present the end portion of the material sidewise to the rolls.

5. A machine for skiving the end portion of a strip of sheet material having, in combination, a pair of feed rolls, a knife having 85 its edge extending obliquely across the gap between the rolls, there being at one end of the rolls a free and unobstructed space for the passage of the body portion of the material, means whereby one roll and with it 90 the knife may be adjusted in the direction of extent of its axis, and a pusher adapted to present the end portion of the material sidewise to the rolls.

6. A machine of the class described having, in combination, a pair of feed rolls, a knife extending at an inclination across the gap between the rolls, one of said rolls being adjustable in a path parallel to the axis thereof, and a carrier for the knife adjustable in a path parallel to that of the roll. 95

7. A machine of the class described having, in combination, a pair of feed rolls, a knife extending at an inclination across the gap between the rolls, one of said rolls being adjustable in the direction of the extent of its axis, the knife being also adjustable in the same direction, and connections between the two such that adjustment of the roll adjusts the knife. 100

8. A machine for skiving the end portion of a strip of sheet material having, in combination, a pair of feed rolls, a knife having its edge extending obliquely across the gap between the rolls, there being at one end of the rolls a free and unobstructed space for the passage of the body portion while the end portion is being skived, means whereby one roll may be adjusted in the direction of extent of its axis, and a mounting for the 115 knife such that the knife is adjusted in the same direction as the roll when the roll is adjusted.

9. A machine of the class described having, in combination, a support for the work, a pair of feed rolls capable of relative movement of separation and approach, a knife inclined to the axes of the rolls substantially from the outermost work-engaging point on one roll to the innermost work-engaging 120

point on the other roll, one of said rolls and the knife being adjustable in the direction of extent of the axis of the roll, and connections between the two such that adjustment of the roll adjusts the knife.

10. A machine for skiving the end portion of a strip of sheet material having, in combination, a support for the strip, a pair of feed rolls one of which is farther from the support than the other, said rolls being capable of relative movement of separation and approach, there being a free and unobstructed space at one end of the rolls to permit passage of the body of the strip while the end thereof is being skived, a knife the effective portion of the edge of which extends substantially from the outer strip-engaging point on that roll which is farther from the support to the inner strip-engaging point on the other roll, means whereby the angular position of the knife varies with the distance between the rolls, means whereby the first-named roll may be adjusted in the direction of extent of its axis, and connections between said knife and roll such that adjustment of the roll adjusts the knife in the same direction.

11. A machine of the class described having, in combination, a pair of feed rolls adapted to advance a piece of sheet material, a knife extending obliquely across the path of the material in position to cut it on an angle and means for bending the material along a line in which the knife intersects the material, said means comprising a cut-away portion on one roll and a cooperating rigid member extending beyond the periphery of the other roll.

12. A machine for skiving the end portion of a strip of sheet material having, in combination, a pair of feed rolls, a knife having its edge extending obliquely across the gap between the rolls, there being at one end of the rolls a free and unobstructed space for the passage of the body portion of the material, means whereby one roll may be adjusted in the direction of extent of its axis, and means for distorting the material at the localities engaged by one end of one roll and by the opposite end of the other roll.

13. A machine of the class described having, in combination, a pair of feed rolls one of which is adjustable in the directions of extent of its axis, the gap between the rolls being open at its outer end to permit free passage of the body portion of the work, and a knife inclined across the roll gap from the outer end of the adjustable roll to the inner end of the other roll, said knife

being mounted for angular movement about an axis which is parallel to the direction of feed movement, and for bodily adjustment in a path parallel to that of the upper roll, the construction and arrangement being such that adjustment of the adjustable roll adjusts the knife bodily while the location of the axis of inclination of the knife remains unchanged.

14. A machine of the class described having, in combination, a pair of feed rolls one of which is adjustable in the directions of extent of its axis, the gap between the rolls being open at its outer end to permit free passage of the body portion of the work, and a knife inclined across the roll gap from the outer end of the adjustable roll to the inner end of the other roll, said knife being mounted for angular movement about an axis which is parallel to the direction of feed movement and is substantially tangential to the upper innermost point on the periphery of said other roll, and for bodily adjustment in a path parallel to that of the upper roll, the construction and arrangement being such that adjustment of the adjustable roll adjusts the knife bodily while the location of the axis of inclination of the knife remains unchanged.

15. A machine for skiving the end of a strip of sheet material having, in combination, a support for the end of the strip, an inclined knife to which the strip is fed sidewise, and means for bending the strip downwardly at the locality in which the upper portion of the knife emerges from the strip and for bending the strip upwardly at the locality in which the lower portion of the knife emerges from the strip so as to produce a scarf having a concave shoulder along its base and a convex edge.

16. A machine for skiving the end of a strip of sheet material having, in combination, a support for the end of the strip, an inclined knife to which the strip is fed sidewise, and means for bending the strip downwardly at the locality in which the upper portion of the knife emerges from the strip and for bending the strip upwardly at the locality in which the lower portion of the knife emerges from the strip so as to produce a scarf having a concave shoulder along its base and a convex edge, the extent of the bending being such that the curves of the shoulder and of the edge are substantially the same.

In testimony whereof I have signed my name to this specification.

WILLIAM THOMAS BUCKINGHAM ROBERTS.
